Robert L. Pennock, Jr., Denver, and Raymond J. Breer, Littleton, Colo., assignors to Heiland Research Corporation, Denver, Colo., a corporation of Colorado

Application December 7, 1950, Serial No. 13,311

Term of patent 7 years

(Cl. D61—1)

To all whom it may concern:

Be it known that we, Robert L. Pennock, Jr., and Raymond J. Breer, citizens of the United States and residents of Denver, city and county of Denver, and Littleton, county of Arapahoe, State of Colorado, whose postoffice addresses are 972 South Gilpin Street, Denver, Colorado, and 206 Cedar Street, Littleton, Colorado, respectively, have invented a new, original, and ornamental Design for a Combined Flashgun and Camera Mount, of which the following is a specification, reference being had to the accompanying drawing, forming part thereof.

Figure 1 is a perspective view of a combined flashgun and camera mount showing our new design;

Figure 2 is a top plan view of the camera mount shown in Figure 1; and

Figure 3 is a side view of the camera mount shown in Figure 1.

The dominant features of our design reside in the portion shown in full lines.

We claim:

The ornamental design for a combined flashgun and camera mount, as shown and described.

ROBERT L. PENNOCK, JR.
RAYMOND J. BREER.
